UNITED STATES PATENT OFFICE.

ALBERT REMAR, OF MAYNARD, OHIO.

RAILWAY-TIE AND CHAIR.

1,312,049.

Specification of Letters Patent. Patented Aug. 5, 1919.

Application filed April 14, 1919. Serial No. 239,929.

To all whom it may concern:

Be it known that I, ALBERT REMAR, a citizen of the United States of America, residing at Maynard, in the county of Belmont 5 and State of Ohio, have invented certain new and useful Improvements in Railway-Ties and Chairs, of which the following is a specification.

The primary object of the invention is to 10 prevent concrete and similar ties from cracking while in use by resiliently mounting the same upon the roadbed whereby a cement tie has all of the advantages of the ordinary wooden tie as well as being substantially 15 everlasting.

A further object of the invention is to 20 provide a resilient chair or seat for a railway tie capable of attachment for proper positioning beneath the tie either upon a straight or curved line of track, the chair possessing great strength and being easily 25 assembled with the tie positioned for use thereon with the chair upon the roadbed.

With these general objects in view, the 30 invention consists of the novel combination and arrangement of parts hereinafter fully described, illustrated in the accompanying drawing and then claimed.

In the drawing forming a part of this 35 application and in which like reference characters designate corresponding parts throughout the several views,

Figure 1 is a side elevation of a tie assembled upon two of my improved chairs, 40 rails being shown in vertical transverse section mounted upon the tie,

Fig. 2 is a top plan view thereof.

Fig. 3 is an enlarged view similar to an 45 end portion of Fig. 1 with parts broken away,

Fig. 4 is a horizontal sectional detail view taken upon line IV—IV of Fig. 6, and

Figs. 5 and 6 are vertical transverse sectional views taken upon lines V—V and 50 VI—VI respectively of Fig. 3.

My invention broadly comprises a channel-shaped chair 10 having upright springs 11 positioned therein for resiliently mounting a concrete or similar tie 12 upon said 55 springs 11 between the longitudinal parallel sides 13 of the chair. Two chairs 10 are provided for each tie 12 being positioned spaced from the opposite ends of the tie and at suitable distances apart for mounting railway rails 14 centrally above the chairs and

secured to the ties properly spaced for the gage of the railway line.

L-shaped recesses 15 are provided in pairs in the lower side of the tie 12 adjacent opposite ends thereof adapted for the reception 60 of upright posts 16 carried by end lugs 17 of the chair 10. Ledges 18 in the recesses 15 extend in similar directions and are provided with slots 19 adapted to receive the post 16 by moving the chair 10 toward the 65 adjacent free end of the tie 12. The posts 16 are provided with heads 20 above the ledges 18 adapted for limiting the upward movement of the tie 12 upon the springs 11.

A retaining pin 21 is positioned transversely through the tie 12, passing through the recesses 15 and the spaced portions of the ledges 18 for retaining the posts 16 in any desired ones of said slots 19. As the 70 posts 16 are fixedly carried by the chair extensions 17, movement of the pins relative thereto is prevented, and where the chairs 10 are laid in parallelism on a curved or slight turn, the ties 12 may be shifted to cause the posts 16 to be received in a different slot so that it is not necessary that the ties extend in true line with the chairs 10. Further, if found impossible to position the chair in exact alinement with the 75 opposite one, due to imperfections in the roadbed, the same may be slightly angularly disposed and the tie received thereon in the usual manner with the posts received in adjacent slots.

The complete operation of the invention 80 will be fully understood, it being seen that the rails 14 are transversely mounted upon the tie 12 centrally above the chairs 10 while the tie 12 is locked in its cushioned position upon the springs 11 of each chair by means 85 of the pins 21. When the chair is employed for a straight line of track, the post 16 will be positioned in the central slots 19 as herein illustrated but when positioned upon a curve, the post 16 at one end of each chair 10 will 90 be positioned in one of the side slots 19 and retained therein by the adjacent pin 21 in a manner that will be readily apparent.

What I claim as new is:—

1. In combination with a tie having L- 105 shaped recesses in the bottom thereof providing ledges extending in the same direction, the said ledges having a plurality of slots, a channel-shaped chair with the tie positioned between the opposite sides there- 110

- of, springs upon said chair with the tie normally seated thereon and movement limiting means at the ends of the chair adjustably secured in said recesses.
5. 2. In combination with a tie having L-shaped recesses in the bottom thereof providing ledges extending in the same direction, the said ledges having a plurality of slots, a channel-shaped chair with the tie positioned between the opposite sides thereof, springs upon said chair with the tie normally seated thereon, lugs projecting from the opposite ends of the chair, upright posts on the said lugs adjustably positioned in said 10 slots, heads upon said posts above said ledges and retaining pins for the posts transversely positioned through the tie and the portions of the ledges adjacent the posts.
- 15 3. In combination with a chair, resilient means upon the chair, a tie seated upon said resilient means and having recesses in the bottom of the tie outwardly of the springs and limiting means upon the chair adjustably positioned within said recesses adapted for retaining the tie angularly positioned 20 relatively of the chair.
4. In combination with a chair, resilient means upon the chair, a tie seated upon said resilient means and having recesses in the bottom of the tie outwardly of the springs, headed posts carried by the chair projecting into said recesses and adjustable retaining means whereby the tie is adapted to be maintained upon the chair in different relatively 25 angular positions.
- 30 35

In testimony whereof I affix my signature.

ALBERT REMAR.
